UNITED STATES PATENT OFFICE.

JULIUS B. KOEHLER, OF CINCINNATI, OHIO, ASSIGNOR TO THE MONITOR STOVE COMPANY, OF CINCINNATI, OHIO, A CORPORATION OF OHIO.

FIRE POT.

Application filed March 29, 1922. Serial No. 547,826.

To all whom it may concern:

Be it known that I, JULIUS B. KOEHLER, a citizen of the United States, and residing at Cincinnati, in the county of Hamilton and 5 State of Ohio, have invented a new and useful Improvement in Fire Pots, of which the following specification is a full disclosure.

This invention relates to improvements in fire-pots, and linings therefor.

10 Objects of the invention are to provide an improved fire-pot, and sectional or segmental lining therefor composed of a plurality of segments or elements, each of which is capable of locking engagement with the 15 pot, and each of which when positioned as a lining therefor conforms to the configuration of the inner surface of the pot, all elements when assembled together, forming a continuous protective wall of even thickness, locked within the pot, and all elements 20 being introducible in directions at right angles to the inner surface of said pot.

Another object is to provide a single means in the form of a key-piece or segment 25 for locking all segments of the lining, after assembly, against either circumferential, or diametric or radial displacement or removal, said key-piece being also introducible in a direction at a right angle to the side of the 30 pot.

Other objects and certain advantages will be disclosed in the description of the drawings forming a part of the specification and in said drawings:

35 Figure 1 is a plan view of my improved fire-pot showing the refractory lining therein, portions of the upper web of the pot being broken away to clearly show, in addition to the general arrangement of the 40 segments, the manner of locking the same by the introduction of a key-piece or locking segment.

Figure 2 is a detailed perspective of one of the fire brick elements, or segments.

45 Figure 3 is a diametric vertical section on line 3—3, Fig. 1.

Figure 4 is a fragmentary section on line 4—4, Fig. 1, illustrating the manner of introducing the segments within the locking 50 grooves of the pot.

The pot 1 is, in this instance, of inverted frustum-conical configuration, although pots of cylindrical configuration are contemplated, and provides upper and lower 55 internal, horizontally disposed, circumfer-

ential webs, respectively 2 and 3, the lower web 3 having an upstanding peripheral rib or flange 5, forming with said web and the wall of the pot, an upwardly facing channel or groove 6, said groove and flange forming 60 a means for pocketing and locking the lower end of the segments or elements of the lining, more fully described hereafter. The upper web also provides a circumferential downwardly directed flange or rib 7 of greater depth than its companion bottom flange, 65 said rib 7 forming with the web and wall of the fire box, a downwardly facing channel or groove 8, of substantially greater depth than the lower groove. The refractory lining of the pot is composed of a plurality of segments or sections 9, the top and bottom ends of which are designed to engage within the grooves 8 and 6, and the said sections are of even wall thickness and, when 70 assembled, their inner faces lie flush with one another and with the inner alined surfaces of the flanges 7 and 5. Each segment or section 9 is of less height or length than the distance between the bottom of grooves 80 and each is provided at its lower inner edge with an angular circumferential notch 10, and at its upper inner edge with a similar circumferential angular notch 11 of greater vertical depth than the notch 10. 75

As shown in Figure 4, each segment or section is introduced by first inserting the upper end of the section into the deeper groove 7 to raise the lower end of the segment sufficiently to clear the rib 5, and subsequently swinging the segment inwardly and against the side of the pot and allowing the section to drop into the lower groove 6, after which the sections or segments assume the position shown in Fig. 3, with the lower end locked in channel 6, and the upper end extending partly into the groove 7, and also locked, thus preventing any possibility of the brick being disengaged from its grooves by tilting inwardly. The sections are thus successively introduced into the grooves until all but the key segment 12 have been assembled, after which the locking or key section 12 is introduced as shown in Figure 1. The section 12 80 is similar to the other sections of the lining except in respect to its side faces 13 which are parallel to one another instead of radial or flared as in the case of the other sections. 85

It will be noted by inspection of Fig. 1 110

that it is impossible to remove the segments 9 after the locking or key section 12 has been introduced. This key-piece is also introduced at a right angle to the side of the pot after all sections have been assembled, introduction in this manner being possible for the reason that the sides 13 are parallel, (as indicated by lines *a*, in Fig. 1) with respect to the radially related sides of the segments 9 at each side thereof.

Having described my invention, I claim:

1. A frustum-conical fire-pot, formed with upper and lower horizontally disposed annular webs having respective downwardly and upwardly directed peripheral flanges, defining with the wall of said pot respectively, relatively deep and shallow opposingly faced grooves, and a lining for said pot comprising tapering circular segments, each having upper and lower interior peripheral angular end notches, said notches and ends engageable with said flanges and grooves for locking said segments within said pot.
2. A frustum conical fire-pot, formed with upper and lower horizontally disposed webs having respective downwardly and upwardly directed flanges defining with the walls of said pot respectively relatively deep and shallow opposingly faced grooves, a lining for said pot comprising tapering segments, said segments providing upper and lower interior peripheral angular end notches, said notches and ends engageable with said flanges and grooves for locking said segments therein.
3. A frustum conical fire-pot, providing upper and lower horizontal webs, having opposingly related circular grooves therein, the upper of greater depth than the lower, a refractory lining for said pot comprising circular segments of refractory material of isosceles trapezoidal configuration, having sides radial with respect to the central axis of said pot and providing upper and lower peripheral angular locking notches, said seg-

ments designed to be successively introduced and locked in said grooves, and a key segment, similar to the said segments, having parallel sides, and designed for lateral introduction as a key-piece for locking all segments against circumferential displacement.

4. A hollow frustum-conical fire-pot, having upper and lower horizontally disposed annular webs providing respectively, relatively deep and shallow opposingly faced grooves, a lining for said pot comprising a plurality of downwardly tapering curved segments of even wall thickness, having their plane end surfaces radially related to the central vertical axis of said pot, and providing upper and lower peripheral angular notches engageable with said flanges for locking said segments therein, the height of said segments being less than the distance between the bottoms of said opposingly related grooves.

5. A hollow frustum-conical fire-pot, providing upper and lower horizontal webs, having opposingly related circular channels therein, the upper of greater depth than the lower, a refractory lining for said pot comprising a plurality of circular segments of refractory material of isosceles trapezoidal configuration, having plane end faces radial with respect to the central axis of said pot and providing upper and lower peripheral angular locking notches, said segments designed to be successively introduced and locked in said grooves, and a key segment, having parallel plane end faces, allowing for its radial introduction as a key-piece for locking all segments against circumferential and radial displacement.

In witness whereof, I hereunto subscribe my name, as attested by the two subscribing witnesses.

JULIUS B. KOEHLER.
